UNITED STATES PATENT OFFICE.

ANDREW ARMSTRONG, OF MARIETTA, GEORGIA.

CONCRETE FENCE-POST.

1,234,601.

Specification of Letters Patent. Patented July 24, 1917.

Application filed June 22, 1916. Serial No. 105,235.

To all whom it may concern:

Be it known that I, ANDREW ARMSTRONG, a citizen of the United States, residing at Marietta, in the county of Cobb and State 5 of Georgia, have invented a new and useful Concrete Fence-Post, of which the following is a specification.

The device forming the subject matter of 10 this application is a concrete fence post, and the invention aims to provide novel means for guiding into place, and for holding in place, a wooden nailing block to which the fence may be secured.

It is within the province of the disclosure 15 to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the 25 invention herein disclosed can be made within the scope of what is claimed without departing from the spirit of the invention.

In the accompanying drawing:—

Figure 1 shows in front elevation, a portion 30 of a concrete fence post embodying the present invention;

Fig. 2 is a side elevation of the structure shown in Fig. 1;

Fig. 3 is a longitudinal section on the line 35 3—3 of Fig. 1; and

Fig. 4 is a cross section taken approximately on the line 4—4 of Fig. 2.

In the accompanying drawings, the numeral 1 indicates a concrete fence post 40 which may be reinforced as at 2. In its forward face, the post 1 is provided with a recess 3 extended entirely across the post from side to side, the recess 3 being reduced at one end to form a pocket 4, lying within

the contour of the post. U-shaped metal 45 straps 5 are embedded in the post 1 and include forwardly presented free ends 6 lying at the sides of the recess 3. A wooden nailing block 7 is inserted into the recess 3, the ends 6 of the straps 5 forming guides to facilitate the insertion of the block into the recess. Securing devices 9 which may be 50 nails or screws pass through the ends 6 of the straps 5 and engage the edges of the block 7. The block 7 is provided at one end 55 with a reduced extension 8 registering in the pocket 4 and preventing the block from moving sidewise during the insertion of the securing devices 9.

Having thus described the invention, what 60 is claimed is:—

A concrete fence post provided in one face with a recess extended entirely across the post from side to side, the recess being reduced at one end to form a pocket lying 65 within the contour of the post; a U-shaped metal strap embedded in the post and including forwardly presented free ends lying at the sides of the recess; a wooden block inserted into the recess, the edges of the block 70 being exposed at the sides of the post, the ends of the strap forming guides which facilitate the insertion of the block into the recess; and securing devices passing through the ends of the strap and engaging the edges 75 of the block, the block being provided at one end with a reduced extension registering in the pocket and preventing the block from moving sidewise during the insertion of the securing device. 80

In testimony that I claim the foregoing as my own, I have hereto affixed my signature in the presence of two witnesses.

ANDREW ARMSTRONG.
